(57) CLAIM

The ornamental design for a vehicle accessory as shown and described.

DESCRIPTION

FIG. 1 is a front view of a vehicle accessory, showing our new design.

FIG. 2 is a rear view of the claimed design.

FIG. 3 is a right side view of the claimed design.

FIG. 4 is a left side view of the claimed design.

FIG. 5 is a top view of the claimed design.

FIG. 6 is a bottom view of the claimed design; and,

FIG. 7 is a first perspective view of the claimed design.

In the drawings, the broken lines depict environmental subject matter only and form no part of the claimed design.
